(57) **CLAIM**

The ornamental design for a linear drain cover, as shown and described.

DESCRIPTION

FIG. 1 is a top perspective view of a first embodiment of a linear drain cover of the present invention;

FIG. 2 is a front view thereof;

FIG. 3 is a rear view thereof;

FIG. 4 is a top view thereof, wherein the bottom view is a mirror image thereof; and

FIG. 5 is a right-side elevation view thereof, wherein the opposing side is a mirror image;

FIG. 6 is a top perspective view of a second embodiment of a linear drain cover of the present invention;

FIG. 7 is a front view thereof;

FIG. 8 is a rear view thereof;

FIG. 9 is a top view thereof, wherein the bottom view is a mirror image thereof; and,

FIG. 10 is a right-side elevation view thereof, wherein the opposing side is a mirror image.

The linear drain cover is shown with a symbolic break in its length in FIGS. 1-4 and 6-9. The appearance of any portion of the article between the break lines forms no part of the claimed design.

The dash-dot-dash broken lines define the boundaries of the claim and form no part thereof. The evenly spaced dashed broken lines in the drawings depict portions of the linear drain cover that form no part of the claim.
